Patented Dec. 22, 1925.

UNITED STATES PATENT OFFICE.

CHARLES H. BUTLER, OF NEW YORK, N. Y.

CROSS-WORD-PUZZLE GAME.

Application filed February 11, 1925. Serial No. 8,468.

To all whom it may concern:

Be it known that I, CHARLES H. BUTLER, citizen of the United States, residing at New York, in the county of New York and State of New York, have invented certain new and useful Improvements in Cross-Word-Puzzle Games, of which the following is a specification.

This invention relates to puzzles and its 10 main object is to provide a game based upon the principle of the widely known cross-word puzzles at present in vogue, with the purpose of forming intersecting words by the movement of a plurality of letter-bearing elements to predetermined positions upon a specially designed surface.

With the above primary object in view, the invention comprises a circumferentially walled board provided with a plurality of 20 cups or pockets relatively arranged so that one of the cups is at the point of intersection of imaginary straight lines passing through the others.

A number of small balls bear letters which 25 if properly arranged spell a plurality of words having one letter in common and by placing the balls in the pockets in a predetermined arrangement with that bearing the common or "key" letter in the pocket at the 30 point of intersection, the object of the game is attained.

The balls are moved into the pockets by 35 tilting, jiggling and otherwise manipulating the board and it will be evident that considerable skill and ingenuity are required to in this manner cause the balls to move into the particular pockets and to remain in place until all of the balls are properly positioned.

40 In order to establish a method for moving the balls to the pockets in more or less systematic order, my invention includes the provision of a depressed ring at or near the periphery of the board, in which the balls 45 are stationed at the beginning of the game, and a number of guide-grooves leading from the ring toward but not to the group of pockets.

The surface of the board is preferably 50 painted or printed in the conventional cross-word puzzle design in order to more impressively convey the meaning and purpose of the game, and the balls each bear their letters at quadrant points of their circumferences at 55 quadrant points of their circumferences so that one of the letters is always visible when the balls are moved upon the

board or after they are placed in the pockets of the same.

It will be readily seen that the game as hereinabove described is not only highly entertaining as a mechanical substitute for the ordinary written cross-word puzzle but is likewise of educational value.

A simple embodiment of my invention has been illustrated in the accompanying drawings in the views of which like parts are similarly designated and in which—

Figure 1 represents a perspective view of the game board;

Figure 2, a central section of the board 70 along the line 2—2, Figure 1;

Figure 3, a section taken on the line 3—3, Figure 1;

Figure 4, an elevation of the five balls 75 adapted for use in connection with the board as shown; and

Figures 5 and 6, fragmentary and reduced face views of the surface of the board, showing two arrangements of the balls in the 80 pockets of the same.

Referring further to the drawings, 5 designates the board which is preferably circular and provided with a peripheral wall or upstanding rim 6.

A group of five pockets is formed in the 85 surface of the board in right-angularly intersecting imaginary lines, one of the pockets 7 being at the point of intersection of the lines and in the center of the board, and the other pockets 8 being located in the lines 90 at equal distances and at opposite sides from the pocket 7.

An annular depression 9 at the periphery of the board represents the "station" where the balls are collected at the beginning of the game and four guide grooves 10 extend radially from the depression 9 in the direction of the group of pockets and merge slantingly into the surface of the board at a distance from the pockets, as shown in 100 detail in Figure 3.

With a board having five pockets as that shown in the drawings, five balls 12 are used as illustrated in Figure 4, each of the balls bearing a letter or other symbol preferably 105 at different points of its surface.

The player designates one of the balls as the "key" ball, i. e., the ball bearing a letter common to the words it is desired to form, and at the same time predetermines what 110 words are to be spelled by the letters on the several balls.

The balls are placed in the "station" ring and the board is tilted, jiggled and otherwise manipulated to cause the balls to pass onto the surface of the board through the 5 guide grooves, and thence into the pockets.

The "key" ball must necessarily be moved into the pocket at the point of intersection of the word-lines and the other balls are caused to move into the other pockets in 10 arrangements corresponding with the adopted words.

For example, the arrangement shown in Figure 5, spells the words "Bug" and "Nut" and that illustrated in Figure 6, the 15 words "Tub" and "Gun" both groups of intersecting words having the common letter "U."

By using the same letters, the words "But" and "Gun" or the words "Gut" and 20 "Bun," or the words "Bun" and "Tug" may be spelled as follows:

G	B	B
B	U	T
N	N	N

It will be readily understood that by using 25 different letters or different numbers or arrangements of pockets and balls a practically endless variety of combinations may be formed, or that by supplying with a board having a definite group of pockets, a number of sets of balls having different letters or symbols, the game may be varied so as to afford instructive amusement with renewed interest each time a new combination of letters is chosen.

The surface of the board is painted or

printed to represent the cross-word puzzle design as stated hereinbefore.

Having thus described my invention, what 40 I claim and desire to secure by Letters Patent is:

1. A cross-word puzzle game comprising a board having a group of pockets arranged in intersecting lines, one of the pockets being at the point of intersection, and a number of balls adapted to rest in the pockets and bearing individual letters capable of spelling a plurality of words having one letter in common. 45

2. A cross-word puzzle game comprising a board having a group of pockets arranged in intersecting lines, one of the pockets being at the point of intersection, and a number of symbol-bearing balls adapted to rest 50 in the pockets, the board having furthermore a depression providing a station for the balls at the beginning of the game, and guide grooves leading from the depression toward but not to the group of pockets. 55

3. A cross-word puzzle game comprising a board having a group of pockets arranged in intersecting lines, one of the pockets being at the point of intersection, and a number of symbol-bearing balls adapted to rest in 60 the pockets, the board having furthermore an annular depression around the group of pockets, providing a station for the balls at the beginning of the game, and guide grooves leading from the depression toward 70 but not to the group of pockets.

In testimony whereof I have affixed my signature.

CHARLES H. BUTLER.
